UNITED STATES PATENT OFFICE.

KARL STASTKA, OF IRWIN, PENNSYLVANIA.

BURGLAR-ALARM.

No. 807,096.

Specification of Letters Patent.

Patented Dec. 12, 1905.

Application filed August 9, 1904. Serial No. 220,101.

To all whom it may concern:

Be it known that I, KARL STASTKA, a subject of the Emperor of Austria-Hungary, residing at Irwin, in the county of Westmoreland and

5 State of Pennsylvania, have invented certain new and useful Improvements in Burglar-Alarms, of which the following is a specification, reference being had therein to the accompanying drawings.

10 This invention has relation to burglar-alarms that are particularly adapted for windows and doors; and the object of this invention is to provide novel means whereby should a burglar enter a window or door an alarm will be sounded, which will signify that the 15 window or door has been entered.

Another object of this invention is to provide novel means which will be suspended upon the interior of the window or door, 20 whereby should a person enter said window or door they will contact with said means and cause an alarm to be sounded, and I have constructed my improved apparatus whereby the same may be readily applied to the ordinary 25 windows and doors commonly used, the construction being such that the expense of manufacture will be reduced to a minimum and a strong and durable construction maintained.

The invention finally resides in the novel 30 construction, combination, and arrangement of parts that will be hereinafter more fully described, and then specifically pointed out in the appended claims.

Referring to the drawings accompanying 35 this application, like numerals of reference indicate corresponding parts throughout the several views, in which—

Figure 1 is a front elevation of a portion of my improved burglar-alarm, showing the 40 same attached to the interior of a window. Fig. 2 is a vertical sectional view of the same. Fig. 3 is a side elevation of a portion of the alarm used in connection with the apparatus shown in Fig. 1 of the drawings. Fig. 4 is a 45 bottom plan view of the alarm and its appurtenant parts, as illustrated in Fig. 3 of the drawings. Fig. 5 is a vertical sectional view of a window-frame, showing a modified form of my improved alarm; and Fig. 6 is a front 50 view of a door, showing my improved alarm attached thereto.

To carry my invention into effect, I have illustrated my improved alarm as being attached to a window and door, and I wish it to 55 be understood that the mechanism employed

to sound an alarm may be readily constructed in connection with a plurality of windows and doors, whereby should either one be entered by a burglar an alarm will be sounded.

Reference will first be had to Figs. 1 and 2 6c of the drawings, wherein I have illustrated an ordinary window-frame having sashes 1 and 2 mounted therein. Centrally of the window and upon the upper cross-frame 3 I secure an angle-iron 4, having a depending arm 5, and 65 to this arm is pivoted, as indicated at 6, an L-shaped rod 7. To the rod 7 is connected in front of the upper and lower sash the frames 8 8, carrying cross-bars 9 9, these frames being constructed of a light material, or they 70 may be made of a netting or any suitable material, whereby should a burglar break the glass or should he lower or raise either sash of the window-frame to enter said window he will contact with these frames. The horizontal portion 10 of the L-shaped rod 7 contacts 75 with a J-shaped lever 11, which is pivoted to a pin 12, carried by the angle-iron 4, and the curved portion 14 of this lever engages a rope or cord 15, which is connected to the wall of 80 the compartment carrying the window-frame, as designated at 16, the other end of said rope passing over a pulley 17, which is rotatably mounted in a bracket 18, carried by the wall 85 of the compartment.

The alarm mechanism, as illustrated in Figs. 3 and 4, consists of a suitable board 19, this board being located in any suitable place in the compartment whereby if the alarm is sounded it will be heard, and the board is 90 mounted in as convenient a place as possible, so that the cord or rope 15 may be attached to the same. Mounted upon the base of the board 19 are the guide-yokes 20 20, and slidably mounted in these guide-yokes is the U- 95 shaped bar 21, which to its one end has connected a cord or rope 22, that passes over a loose pulley 23, mounted upon said board, this cord or rope 22 having a weight 24 attached to its lower end. Pivotaly mounted, as design- 100 ated at 25, is a three-pronged bell-crank lever, which includes a clapper-arm 26, that carries a clapper 27. The reference-numeral 28 designates another prong or arm of the bell-crank lever, this prong extending rearwardly and being bent outwardly, as indicated at 29. The bell-crank lever has another depending prong 30, which is normally adapted to engage one of the pins 31 31, carried by a wheel 32, that is rotatably mounted upon a 105

shaft 33, this wheel having formed integral with its hub portion a drum 34, and wound around said drum is a rope or cord 35, having connected to its loose ends weights 36 36. The 5 reference - numeral 37 designates a spring which is secured to the board 19 and normally tends to throw the hammer against the bell, the upper arm of slide 21 forming an abutment for the hook 29 to hold the hammer-arm 26 from being oscillated by pins 31. Secured to the upper edge of the board is a suitable bell 38, which is placed in such a position that when the bell-crank lever is moved the clapper 27 will strike said bell and sound an 10 alarm.

The operation of the mechanism just described is as follows: We will assume that a person has entered the window and has contacted with either one of the frames 8 8, at 15 which time said frame will be swung outwardly in the direction of the arrow 39. (Shown in Fig. 2 of the drawings.) As either one of said frames is swung outwardly it carries with it the rod 7, and the horizontal portion 10 of said rod will be raised, permitting the lever 11 to swing upon its pivot and release the rope or cord 15. As this rope or cord is released the weight 24 will draw the bar 21 through the guide-yokes 20 20, the rope 15 being attached to the outer end of said bar. As this 20 bar is drawn along the board the end of the bar, as designated by the reference-numeral 40, is carried past the rearwardly-extending prong 28, and the withdrawing of this bar 25 will in a manner form a clear path for the downward movement of the rearwardly-extending prong 28. When said bar 21 has assumed this position, the bell-crank lever will be rotated upon its pivot 25 by one of the 30 weights 36 moving downwardly and through the medium of the drum 34 will rotate the wheel 32 and cause the pins 31 carried by said wheel to strike the depending prong 30 of the bell-crank lever, the rapid rotation of the 35 wheel 32 causing each pin to engage the prong 30, actuating the bell-crank lever to sound a plurality of successive alarms. After each pin 31 has engaged the prong 30 it and the prongs 26 and 28 will be returned to their normal position by the spring 37. By making the drum 34 of a sufficient diameter and providing the same with a considerable length of rope or cord 35 the alarm may be made to sound an alarm for quite a period of time or until the 40 bar 21 is manipulated to place the end 40 of said bar in the path of travel described by the rearwardly-extending prong 28.

In Fig. 5 of the drawings I have illustrated a modification wherein the mechanism comprising the pin 12 and the lever 11 are mounted under the upper cross-frame 3 of the window-frame, this construction being employed to permit the easy placing of shade-rollers and curtains on the window-frame.

65 Reference will now be had to Fig. 6 of the

drawings, wherein I have illustrated a door having a plate-glass front, and upon the door is secured my improved burglar-alarm. In this instance the frames 8 8 are formed of an L-shaped rod 7' and cross-bars 9', said frame 70 being pivotally mounted, as indicated at 6', to a plate 14', that is secured to the frame of the door, and to the plate 14' is pivoted a lever 11', which engages a rope 15', similar to the rope 15, heretofore described. Upon the 75 glass being broken and the opening entered by a burglar the frame will be swung outwardly, similar to that heretofore described, and the rope 15' released to sound an alarm. Should the door be opened without breaking 80 the glass, the lever 11' will be disengaged from the rod and permit the weight 24 to draw said bar 21 and rope into such a position that an alarm will be sounded.

While I have herein shown the frames as 85 being rectangular and composed of ordinary cross-bars, it is obvious that these obstructions may be made of any desired ornamentation or configuration, and I do not care to limit myself to the specific mechanism shown, 90 but may employ such mechanism whereby the same results will be obtained.

Having fully described my invention, what I claim, and desire to secure by Letters Patent, is—

1. The combination with a frame adapted to be pivotally suspended in front of a building-closure, said frame being formed with a projecting horizontal portion, of a swinging lever pivotally suspended from the window-frame and having a hooked end, said lever engaging the projecting portion of the frame a rope engaged by said hooked end, an alarm, a sliding bar connected to said rope and engaging the clapper of the alarm, a weight attached to said sliding bar and adapted to move the same out of engagement with the clapper of the alarm when said rope is released by the hooked lever.

2. In a burglar-alarm the combination with 110 a frame adapted to be pivotally suspended at its upper edge in front of an opening in the building, a hooked lever adapted to be pivotally suspended adjacent to said frame and engaged thereby, a cord fixed at one end and attached to a sliding bar at the other end, said cord being engaged by said hooked lever, means for moving said sliding bar when the tension on said cord is released, an alarm mechanism, and means whereby when the 115 cord is released and the sliding bar allowed to move the alarm mechanism will be thrown into action.

3. In a burglar-alarm, the combination of a frame adapted to be pivotally suspended at its 120 upper edge in front of an opening in a building, means for pivotally suspending said frame at its upper edge, a hooked lever adapted to be pivotally suspended adjacent said frame and engaged thereby, a cord secured at one 125 130

end and engaged by said lever, alarm mechanism, a locking-bar arranged adjacent said alarm mechanism, and adapted to normally maintain the mechanism in passive condition, 5 said cord being connected to said locking-bar, and said parts being so constructed and arranged that, when the tension of the cord is relieved by the swinging of the frame, the

locking-bar will release the alarm mechanism and the alarm will be sounded. ¹⁰

In testimony whereof I affix my signature in the presence of two witnesses.

KARL STASTKA.
